EMERGENCY SIGNAL TRANSMITTER FOR
AIRPLANES OR THE LIKECharles A. Koster, Phoenix, and Wayne E. Perry, Tempe,
Ariz., assignors to Aero Electronics Development Co.,
Inc., Tempe, Ariz.

Filed Apr. 6, 1973, Ser. No. 348,730

Term of patent 14 years

Int. Cl. D29—02; D14—03

U.S. Cl. D10—16

FIG. 1 is an exploded view of an emergency signal transmitter for airplanes or the like showing our new design;

FIG. 2 is a perspective view thereof on a reduced scale.

The undisclosed side of the transmitter is plain. The antenna is broken away to indicate indeterminate length.

We claim:

The ornamental design for an emergency signal transmitter for airplanes or the like, as shown and described.
